(57) **CLAIM**

I claim the ornamental design for a flexible compressible brush for cleaning drinking straws, as shown and described.

DESCRIPTION

FIG. 1 is a perspective view of a flexible compressible brush for cleaning drinking straws showing my new design; FIG. 2 is a front elevational view thereof, the rear elevational view being identical thereto;

FIG. 3 is a side elevational view thereof, the elevational view of the opposing side being identical thereto;

FIG. 4 is an enlarged top plan view thereof; and,

FIG. 5 is an enlarged bottom plan view thereof.
